UNITED STATES PATENT OFFICE.

CHARLES A. LINDSTRÖM, OF PITTSBURG, PENNSYLVANIA, ASSIGNOR TO PRESSED STEEL CAR COMPANY, OF PITTSBURG, PENNSYLVANIA, A CORPORATION OF NEW JERSEY.

CAR-DOOR GEAR.

No. 900,941.

Specification of Letters Patent.

Patented Oct. 13, 1908.

Application filed April 15, 1908. Serial No. 427,191.

To all whom it may concern:

Be it known that I, CHARLES A. LINDSTRÖM, a citizen of the United States, residing at Pittsburg, Northside, Allegheny 5 county, Pennsylvania, have invented certain new and useful Improvements in Car-Door Gears, of which the following is a full, clear, and exact description.

The object of the present invention is to 10 provide a modification of the structure shown and described in my application for Letters Patent entitled "Car door operating mechanism", filed November 20th, 1907, Serial No. 402,989, in which a door operating and locking mechanism is disclosed comprising a door closing shaft with suitable levers or arms thereon to raise the doors, a door locking shaft movable bodily into door locking position and suitable connections between the 15 two shafts whereby they are operated in proper sequence.

In the hereinbefore mentioned application and in the present structure is employed an oscillating gear interposed between the two 20 shafts and operated by a pinion carried by a door locking shaft, which pinion is in turn operated by a suitable hand lever operated gear. When the oscillating gear has reached a certain period in its rotation, by suitable 25 means, the pinion carried by the door locking shaft is caused to travel over said oscillating gear to carry the shaft into door locking position. A suitable cam operated stop is provided for holding the door locking shaft in its 30 non-locking position while the doors are being closed, which also permits the shaft to move from locking to non-locking position when the doors are being opened. Furthermore, a suitable means is employed for causing 35 a parallel movement of the two ends of the door locking shaft and finally a suitable connection or link is provided which connects the oscillating gear and the door closing shaft.

40 The present invention provides a modified connection between the oscillating gear and door operating shaft.

Referring now to the drawings, in which like characters refer to like parts, Figure 1 is 45 a plan view partly in section of one corner of a car embodying my invention and Fig. 2 is an end elevation of the same.

Referring now in detail to the drawings, 1 represents a center sill or center sill structure, 50 2 the end wall of the car, 3 the end sill, 4 the

side, 5 the drop doors, 6 a cross-bearer, 7 the door raising shaft, 8 door raising arms carried by shaft 7, and 9 the wearing shoes carried by doors 5.

10 is a bodily movable door locking shaft, 60 11 a gear rigidly carried by shaft 10 and 12 a pinion carried by stud 13 for driving gear 11.

14 is a hand lever also mounted on stud 13 carrying pawl 15 for driving pinion 12.

16 is a dog for preventing back movement 65 of pinion 12.

Stud 13 is mounted in a movable frame 17 and supported at its outer end by shaft 10 and at its inner end by stud 18 which extends through slot 19 in frame 17. 70

20 is a slotted stop plate mounted to oscillate in end sill 3 and embracing shaft 10. Plate 20 is provided with a cam projection 21 co-acting with a cam 22 mounted on stud 23 seated in end sill 3. 75

24 is a gear which is driven by pinion 11' mounted on shaft 10. In the structure described in the said application and in this application gear 24 is provided with suitable connection between it and the door raising 80 shaft 7. It is this latter portion of the mechanism which constitutes the subject matter of the present invention, and which parts will now be described as a modification of the structure shown in the hereinbefore mentioned application: Instead of employing a stop, a link and a crank arm as shown in my previous application, in the present structure I mount a pinion 25 on stud 23 and a pinion 26 on shaft 7 which are connected by link 27 85 having therein slots 28 29, one at each end. The slot 28 receives the stud 23 and slot 29 receives a stud 30 seated in shaft hanger 31. Link 27 is furthermore provided with teeth 32 which engage pinion 26 and teeth 33 which 90 engage pinion 25.

The operation of the structure described is as follows: Assuming the doors to be closed as shown in the drawings, lever 14 is grasped after dog 16 has been thrown out and pawl 100 15 reversed and moved from the side of the car toward the center of the car in the direction of the arrow, Fig. 1. This will rotate gear 11 in the direction of its arrow and pinion 11' in the same direction. As there is no 105 resistance to the travel of shaft 10 from the door locking position to the non-locking position, pinion 11' will travel over the teeth of gear 24 until it reaches the outer end of the slot in stop plate 20. As soon as the locking 110

shaft is removed from its position beneath the doors the weight of the doors and the lading thereon causes the doors to drop instantly discharging the lading. The dropping of the doors under this condition striking arms 8 causes a rotation of shaft 7 in the direction of its arrow, throwing link 27 forward causing a rotation of gear 24 and further rotation of pinion 11' on the shaft, the shaft 10 turning in its journal in the outer end of the stop plate 20. Meanwhile cam 22 turning in the same direction as gear 24 has thrown cam projection 21 on stop plate 20 upwardly so that the slot in stop plate 20 extends upwardly instead of horizontally, thus effectively locking shaft 10 in its outer or non-door position. The doors now being open and it being desired to close the same, pawl 15 is thrown to the position shown in Fig. 1. Dog 16 is also thrown into engagement with pinion 12 and the lever is moved in a direction opposite the arrow; Fig. 1. This causes a rotation of gear 11 in the direction of its arrow and rotation of pinion 11' in a like direction. As the shaft is now locked against inward movement because of the position of stop plate 20, the rotary motion of the pinion 11' is transmitted to gear 24 causing gear 24 to rotate in the direction opposite its arrow which throws edge of link 27 towards the center of car rotating pinion 26, shaft 7 and arms 8 to raise the doors to a nearly closed position. At the moment when doors reach such a position the position of cam 22 on stud 23 permits cam projection 21 to drop bringing the slot in the top plate 20 to a horizontal position. At the same time stud 30 has reached the outer end of slot 29 so that further rotation of gear 24 is prevented so that further operation of the hand lever 14 causes the pinion 11' to travel over the teeth of gear 24 carrying the shaft 10 to its door locking position.

As shown and described in my previous application herein referred to, the movement of the ends of shaft 10 are maintained parallel by a suitable device which may be employed in connection with the present structure. As also is shown in my said previous application, inward movement of the shaft 10 causes a final elevation of the doors to carry them from the lifting arms 8.

The structure herein described and shown comprises but a portion of the entire car door operating gear, but is sufficient to illustrate the principle of its operation and the structure of its parts. Customarily the mechan-

ism thus described operates but one-fourth of the total number of doors in a car.

Having thus described my invention, the following is what I claim as new therein and desire to secure by Letters Patent:

1. In a car door gear, a door, means for closing said door, door supporting means geared to said door closing means to move into door supporting position when the door is closed, and means for operating the mechanism, said gearing comprising a horizontally movable link.

2. In a car door gear, a door, means for closing said door, door supporting means geared to said door closing means to move into door supporting position when the door is closed, and means for operating the mechanism, said gearing comprising a rack bar or link geared to said door closing means and to said door supporting means.

3. In a car door gear, a door, means for closing said door, door supporting means geared to said door closing means to move into door supporting position when the door is closed, and means for operating the mechanism, said gearing comprising a rack bar or link, a gear train connecting said door supporting means with said bar or link and a pinion connecting said bar or link with said door closing means.

4. In a car door gear, a door, means for closing said door, a bodily movable door supporting shaft, a rack bar or link geared thereto and to said door closing means to move said shaft to door supporting position after the door has been closed and means for operating said mechanism.

5. In a car door gear, a door, means for closing said door, a movable door supporting device, a pinion for operating said device, a gear meshing with said pinion, a pinion moving with said gear, a stud on which said last named gear and pinion turn, a slotted rack bar or link engaging the under side of said last named pinion and supported at one end by said stud and a pinion carried by the door closing means, engaging the under side of said rack bar or link and supporting the bar or link at the opposite end.

The foregoing specification signed at McKees Rocks, Allegheny county, Pennsylvania, this 6th day of April, 1908.

CHARLES A. LINDSTRÖM.
